UNITED STATES PATENT OFFICE.

CHARLES C. PARKER, OF BALTIMORE, MARYLAND.

BOTTLE-CAP SEAL AND METHOD OF MAKING THE SAME.

Application filed May 28, 1926. Serial No. 112,302.

This invention relates to seals for metal body caps, and to a method of making the same. Seals of this character usually consist of disks of compressible material, such as cork, and sometimes such seals are faced with smaller disks of thin material which is impervious to water. The facing disk is intended to contact with the inner part of the lip of the bottle, to prevent the contents of the bottle from coming in contact with the cork, or from seeping through to the metal cap, and also to prevent particles of cork from dropping into the liquid. The margin of the disk of compressible material is left free to undergo compression when the cap is applied to the bottle by a capping machine. The seals, with or without the facing disks, are usually cemented into the metal caps and the facing disks are applied in various ways, usually by the use of cement. In the subsequent handling of the caps, as when they are in the hoppers of the automatic capping machines, it not infrequently happens that the facings will drop off of some of the seals, and also the seals will drop out of the caps.

The purpose of the present invention is to provide a bottle cap seal having a facing disk which can be readily applied to the compressible disk and which interlocks with the latter so that it cannot become readily detached, and this facing disk co-operates with the compressible disk to expand the marginal portion of the latter into the flutings of the metal cap when the seal is pressed into the cap. The facing disk is thus mechanically held to the compressible disk so that no cement is required between the disks, and the compressible disk is wedged within the cap so that the seal will not drop out of the cap even though the seal be imperfectly cemented to the cap.

In carrying out the invention, I take a disk of cork, or other suitable compressible material, adapted to fit within the ordinary crimped bottle cap, and by means of suitable tools, I bend the marginal portion of this disk out of the plane of the central portion, thus producing a state of tension in a circular zone near the margin of the disk on one of its sides. With a cutting tool, I make a circular slit, concentric with the periphery of the disk, in the part of the disk which is under tension. As soon as this cut is made the walls of the slit spread apart, forming a V-shaped circular groove which extends

a little more than half through the compressible disk. The facing disk is preferably made of thin celluloid with a flange adapted to fit in the groove formed in the disk of compressible material. The flanged disk is then, by suitable mechanism, placed over the compressible disk, with its flange extending into the groove in the latter, and pressure is applied to the two disks, which has the effect of crumpling the flange of the facing disk and of flattening the marginal portion of the compressible disk into the plane of the body of said latter disk. The walls of the circular groove thus grip the flange of the facing disk and become interlocked with it. When the pressure is relieved, the margin of the compressible disk is held, by the flange of the facing disk, at a slight angle to the body of the former, making the seal slightly convex on the side opposite the facing. As the metal bottle caps are generally concave on their inner faces, when the seal is pressed into the cap, with its concave face next to the concave face of the cap, the seal buckles and its marginal portions are forced into frictional engagement with the crimps in the cap flange. While thus held, it is impossible for the facing to drop off of the compressible disk and the cap will stand ordinary handling without causing the seal to drop out, even though the latter be not cemented in place; or, if the seal is cemented to the cap, as is customary, the seal will be held frictionally within the cap even though the cementing be imperfect. The facing may also be cemented to the compressible disk, although this is not essential for securing the facing to the disk.

In the accompanying drawing, in which the seal and the method of making and applying it are illustrated,

Fig. 1 is a perspective view of a disk of compressible material, such as cork as commonly used in seals for bottle caps;

Fig. 2 is a central section through the same, showing the marginal portion of the disk bent out of the plane of the body of the disk;

Fig. 3 shows the disk after an annular slit has been made in the disk on the side and in the zone which was put under tension by bending down the margin of the disk;

Fig. 4 shows the flanged facing disk in position to be applied to the compressible disk;

Fig. 5 shows the facing disk applied to the

compressible disk, and the marginal portions of the latter flattened out by pressure;

Fig. 6 shows the completed seal after the pressure has been relieved; and,

5 Fig. 7 shows the seal in place in a metal bottle cap.

Referring to the drawing, *a* indicates a disk of cork, cork composition, or other compressible material, suitable for making a 10 bottle cap seal; *b* indicates a facing disk, and *c* indicates a crimped metal bottle cap. In carrying out the invention, the marginal portion 1 of the compressible disk is bent downwardly out of the plane of the body portion 2, by a suitable press, not shown, and the 15 material at one side of the disk is thus put under tension in a circular zone at the angle 3 between the marginal portion and the body portion of the disk. While the disk is thus bent, a suitable cutting tool forms an annular slit, concentric with the margin of the 20 disk in the zone where the material is under tension, and the walls of this slit immediately spread, forming the V-shaped groove 4 shown in Fig. 3.

The facing disk *b*, which is relatively thin and preferably made of celluloid, has a flange 5, and after the slit has been made in the compressible disk, the facing disk is brought 30 into the position shown in Fig. 4 and the two disks are then pressed together, the flange 5 entering the circular slot 4. This compression of the disks causes the marginal portions of the disk *a* to flatten out and also 35 causes the flange of the facing disk to crumple, as shown at 5^a, in Fig. 5, and the walls of the slot thus become interlocked with the flange on the facing disk. When the pressure is relieved, the marginal portion of the 40 disk *a* is bent slightly out of line with the body portion by reason of the presence of the flange 5^a in the slot. The finished seal, shown in Fig. 6, is thus slightly convex. The cap, made of sheet metal, comprises the 45 body portion 6, slightly concave on its inner side, and a crimped flange 7. The completed seal is pressed into the cap, with its concave side facing the inner concave surface of the cap, and this pressure causes the seal to 50 buckle, as shown in Fig. 7, and the marginal portion 1 of the seal is thus forced outwardly against the crimps in the cap, this marginal portion being somewhat 55 stretched by the bending operation, and also pressed outwardly by the flange on the facing disk, which fills the slit cut in the compressible disk, and to that extent expands the marginal portion. The seal will ordinarily be also secured within the cap by suitable 60 cementing material, as indicated at 8.

What I claim is:

1. The method of making bottle cap seals, each composed of a disk of compressible material and a smaller flanged disk of waterproof material, which comprises bending the 65 marginal portion of the compressible disk out of the plane of its body portion to produce a state of tension in a circular zone on one side of said latter disk, making an annular slit on said side of the compressible 70 disk and in said zone, placing said flanged disk on said side with its flange in the slit, and pressing said disks together to flatten the seal and cause the walls of the slit to grip said flange.

2. The method of making bottle cap seals, each composed of a disk of compressible material and a smaller flanged disk of waterproof material, which comprises bending the marginal portion of the compressible disk 80 out of the plane of its body portion to produce a state of tension in a circular zone on one side of said latter disk, making an annular slit on said side of the compressible disk and in said zone, placing said flanged 85 disk on said side with its flange in the slit, and applying pressure to said disks sufficient to crumple the flange and flatten the seal.

3. A bottle closure comprising a metal cap, a disk of compressible material within the 90 cap, said disk having a circular slit adjacent its periphery, and a thin disk of waterproof material having a peripheral flange fitting in said slit.

4. A bottle closure comprising a metal cap, 95 a disk of compressible material within the cap, said disk having a circular slit adjacent its periphery, and a thin disk of waterproof material having a peripheral flange fitting in said slit, said flange being annularly crimped 100 and interlocked with the walls of the slit.

5. A seal for crimped metal bottle caps comprising a disk of compressible material having a circular slit adjacent its periphery and a disk of waterproof material having 105 a peripheral flange fitting in said slit.

6. A seal for crimped metal bottle caps comprising a disk of compressible material having a circular slit adjacent its periphery and a disk of celluloid having a peripheral 110 flange fitting in said slit.

7. A seal for crimped metal bottle caps comprising a disk of compressible material having a circular slit adjacent its periphery and a disk of waterproof material having a 115 peripheral flange fitting in said slit and interlocked with the walls thereof.

In testimony whereof I hereunto affix my signature.

CHARLES C. PARKER.
